UNITED STATES PATENT OFFICE.

JONAS F. BRIOR, OF EASTON, PENNSYLVANIA.

RATCHET-WRENCH.

1,273,726.

Specification of Letters Patent.

Patented July 23, 1918.

Application filed June 20, 1917. Serial No. 175,919.

To all whom it may concern:

Be it known that I, JONAS F. BRIOR, a citizen of the United States, residing at Easton, in the county of Northampton and State of Pennsylvania, have invented certain new and useful Improvements in Ratchet-Wrenches, of which the following is a specification.

This invention relates to wrenches and more particularly to the class of ratchet wrenches.

The primary object of the invention is to provide an improved ratchet wrench having adjustable gripping jaws mounted to rotate when the handle of the wrench is actuated so that the nut to which the wrench is applied may be turned.

Another object of the invention is to provide a rotatable ratchet disk adapted to be rotated in one direction when the handle of the wrench is reciprocated so that the jaws carried by the disk will rotate around a common center and within a minimum space.

A further object of this invention is the provision of a ratchet wrench which consists of comparatively few parts and is simple in construction, but durable and well adapted to withstand the rough usage to which devices of this character are ordinarily subjected.

For a full description of the invention and the advantages and merits thereof, reference is to be had to the following description and the accompanying drawings, wherein is illustrated the preferred form of my invention, in which:

Figure 1 is a side elevation.

Fig. 2 is a longitudinal section.

Fig. 3 is a section on the line 3—3 of Fig. 1.

Fig. 4 is a section on the line 4—4 of Fig. 2.

Referring to the drawing, wherein is illustrated the preferred form of my invention, and in which like numerals of reference indicate corresponding parts throughout the several views, the head of the wrench includes a casing 1 which is of circular formation and of comparatively shallow depth. The ends of the casing are partially closed by circular rings 2 and 3 which are secured to the casing through the medium of fastening screws 4 or the like and its rings overlap a portion at each end of the casing to form retaining flanges. Mounted in the space embraced by the casing is a rotatable ratchet disk 5 having a plurality of circum-

ferentially spaced teeth 6 on its marginal edge. The diameter of this ratchet disk is slightly less than the interior diameter of the casing so that the disk is permitted to 60 freely rotate within the casing. A handle 7 is integrally formed with or otherwise fastened to the casing and its handle is divided into two sections pivotally connected together on a pivot pin 8 extending through 65 the overlapping portions of the handle sections. An enlarged portion 9 of the handle is provided with an opening 10 communicating with the interior of the casing and a locking pin 11 is mounted in the opening 70 and extends into the casing. This pin, as shown to advantage in Figs. 1 and 2 of the drawing projects outwardly from the enlarged portion 9 of the handle through a shield 12 fixed to the handle and which has 75 an opening for receiving the pin. Surrounding the pin and mounted in an enlarged portion of the opening 10 is a coil expansion spring 13 engaging a flange 14 formed on the pin to urge the pin into the 80 casing for engagement with the teeth 6 of the ratchet disk. The pin has its inwardly projecting end beveled so that the disk is free to rotate in one direction but will be prevented by the straight side of the pin 85 from rotating in the opposite direction.

The central portion of the ratchet disk 5 is provided with a rectangular opening 15 communicating with one edge of the disk at which point the teeth are removed. The 90 side walls of this opening are provided with longitudinally extending slots 16 and 17 in which are received the tongues 18 of the movable jaws 19 and 20 thus holding the jaws in a restricted path whereby they may 95 be moved toward or away from each other for adjustment to various sizes of nuts or bolts. The open end of the opening 15 is closed, after the jaws have been placed into position, by the closure 21 which fits into 100 the end of the opening 15 and has oppositely disposed lugs extending into the ends of the grooves 16 and 17, the lugs being provided with openings through which fastening pins 22 are extended whereby the closure may be 105 fastened to the disk. This closure has a number of teeth 23 formed thereon corresponding in pitch and shape to the teeth 6 of the disk so that after the closure is mounted in position an unbroken series of 110 teeth will extend around the outer end of the disk.

Formed in the disk, at the bottom of the groove 17 is a recess communicating with the groove and adapted to receive an adjusting bolt 24 one half of which is provided with 5 right hand screw threads and the other half being provided with left hand screw threads. One end of this adjusting bolt 24 is received in a depression 25 formed by an extended portion of the recess and the opposite end of 10 the bolt has a kerf to receive a screw driver or the like whereby the bolt may be rotated. Intermediate the ends of the groove 17 and the recess, the disk is cut out to form a notch 26 within which a knurled barrel 27 is arranged and which is fixed to the adjusting 15 screw 24. The tongue 18 of the jaw 20 which is received in the groove 17 is provided with screw threads engageable with the screw threads on the corresponding end 20 of the adjusting bolt 24. The tongue 18 of the opposite jaw 19 is also provided with oppositely formed screw threads engaging the screw threads of the corresponding ends 25 of the adjusted bolt so that when the latter is rotated the jaws will be caused to move toward or away from each other according to the direction of rotation of the adjusting bolt.

This rotary movement of the bolt is accomplished through the medium of the knurled barrel 27 which the operator may manipulate with his fingers.

After being assembled in the manner above described the jaws may be applied to 30 a bolt or nut and by swinging the handle in one direction the pin will freely ride over the edge of the teeth 6 and 23 while swinging movement of the handle in the opposite direction will cause the pin to turn the 35 ratchet disk thus imparting the necessary movement to the jaws for turning the nut or bolt.

From the foregoing it will be observed that a very simple and durable ratchet

wrench has been provided, the details of 45 which embody the preferred form. I desire it to be understood, however, that slight changes in the minor details of construction may be made without departing from the spirit of the invention or the scope of the 50 claims hereunto appended:

1. In a ratcliet wrench, the combination of a handle having a casing mounted at one end, a disk rotatably mounted in the casing and provided with teeth at its marginal edge 55 and having a diametrically extending slot opening at one edge of the disk, a pair of jaws mounted for sliding movement in the slot, one end of the slot having a closure mounted therein and provided with teeth to 60 complete an annular series of teeth for the said disk, and means carried by the disk and engageable with the jaws to move the latter toward and away from each other through the said slot. 65

2. In a ratchet wrench, the combination of a handle having a casing mounted at one end, a disk rotatably mounted in the casing and provided with teeth at its marginal edge and having a diametrically extending slot 70 opening at one edge of the disk, a pair of jaws mounted for sliding movement in the slot, one end of the slot having a closure mounted therein and provided with teeth to 75 complete an annular series of teeth for the said disk, and means carried by the disk and engageable with the jaws to move the latter toward and away from each other through the said slot, the said closure having lugs fixed to the said disk for maintaining the said closure in rigid position at the end of the said slot. 80

In testimony whereof I affix my signature in presence of two witnesses.

JONAS F. BRIOR.
